UNITED STATES PATENT OFFICE

JACOB TELLER AND ARTHUR P. SCHULZ, OF NEW YORK, N. Y., ASSIGNORS TO TELLER CORPORATION, OF CHATTANOOGA, TENNESSEE, A CORPORATION OF TENNESSEE

DESIGN FOR A GAS OR ELECTRIC CABINET COOKSTOVE OR RANGE

Application filed July 27, 1931. Serial No. 40,699. Term of patent 7 years.

To all whom it may concern:

Be it known that we, JACOB TELLER and ARTHUR P. SCHULZ, citizens of the United States, and residents of New York city, in the county of New York and State of New York, have invented a new, original, and ornamental Design for a Gas or Electric Cabinet Cook Stove or Range, of which the following is a specification, reference being had to the accompanying drawings, forming a part thereof.

Figure 1 is a front perspective view of the cook stove or range, with the cover raised;

Figure 2 is a fragmentary top perspective view thereof, with the cover closed; and

Figure 3 is a side elevation thereof.

We claim:

The ornamental design for a gas or electric cabinet cook stove or range, as shown.

JACOB TELLER.

ARTHUR P. SCHULZ.
